HYDRAULIC SYSTEM EMBODYING MEANS FOR DEPRESSURIZING CYLINDERS WITHOUT SHOCK
Donald W. Van Doorn and William C. Pease III, Columbus, Ga., assignors to Lummus Cotton Gin Company, a corporation of Georgia

Filed Aug. 9, 1960, Ser. No. 48,526
9 Claims. (Cl. 121—38)

Our invention relates to hydraulic systems and has for its principal object the provision of means associated with such systems whereby upon depressurizing a hydraulic cylinder or other pressure device, depressurization is accomplished without hydraulic shock.

In the art to which this invention relates it is known that tremendous hydraulic shock is obtained in the conduits, valves and other parts of hydraulic systems when high pressure cylinders or the like are depressurized. That is, in systems heretofore existing, such for instance as in hydraulic systems for baling cotton and the like, when the main valve controlling the admission of fluid under pressure to the cylinder was opened, shocks of extremely high order were imposed on the conduits and other parts of the equipment. In presses which operate at around 2,000 pounds per square inch, this sudden release of high volume, high pressure oil when the cylinder is depressurized has caused serious damage to the piping and the like. It has been possible, heretofore, to solve this problem in part. However, the apparatus necessarily employed to accomplish this improvement has been complicated and expensive, almost to the degree that its use has been prohibitive on certain types of equipment.

In view of the foregoing a prime object of our invention is to provide apparatus which is economical, simple and trouble free in operation and which may be associated with hydraulic systems embodying high pressure cylinders, rams or the like and which is effective to permit the ram to be depressurized without any appreciable hydraulic shock to the system.

Another object of our invention is to provide apparatus of the character designated which is applicable both to single acting and double acting cylinders or rams.

Another object is to provide depressurization means for high pressure rams or the like in which we provide, in fluid by-passing relation to the main flow valve, a smaller valve together with means to open the smaller valve prior to opening the main valve, thereby bleeding off a relatively small quantity of the total quantity of fluid, relieving the pressure and thereby permitting the main valve subsequently to open without producing the aforementioned hydraulic shock or hammer in the lines.

Another object of our invention is to provide depressurization means for both double and single acting hydraulic cylinders which is effective for the purposes indicated without materially increasing the length of time required to bring the cylinder up to pressure and without materially increasing the length of time required to depressurize the cylinder.

A further object is to provide a pilot or control valve associated with the main valve in such manner that the actuation of the pilot valve to depressurize the cylinder also automatically brings into operation the subsequent opening of the main valve, whereby the main valve either is opened or permitted to open simply by the operation of the pilot valve.

2

Briefly, we show our invention as being associated alternately with a single acting and a double acting ram. In the former case we prefer to use a spring loaded, differential piston main valve together with check valves and a spring loaded check valve associated therewith and a pilot valve effective to control the operation of the main valve. In essence, we so arrange the spring loaded check valve and the small hydraulic pilot lines relative to the main valve that on the larger end of the differential piston thereof, in initial operation of the system, there is developed enough pressure to overcome a spring provided in the main valve, thereby to close off the return port from the cylinder to the reservoir. When the pressure in the main line, which is applied to the small end of the valve and also to the large piston end, drops below the pressure of the spring, then the spring in the differential piston valve comes into play and opens the valve.

In the case of the double acting cylinder we preferably employ a main, spool type four-way valve which is hydraulically operated from the pilot valve. That is, we provide a main valve which has a spring return to neutral position and move the spool thereof to proper operating position by hydraulic connections from the pilot valve.

As the description proceeds, it will be apparent that our invention embodies the concept of maintaining a hydraulic unbalance which holds the main valve closed during the period of time that the cylinder is being depressurized. The high pressure fluid is bled off through a small pilot valve or the like until the system pressure lowers to a point that is safe to allow the main valve to open without shock to the system. At this pressure the hydraulic unbalance changes allowing the main valve to open, eliminating hydraulic shock or hammer. Further, our invention is particularly adapted for use in connection with fiber presses such as cotton baling apparatus. Therefore, we show in this application suitable electrical controls as a part of our system and which make our invention entirely suitable for the operation and control of baling presses.

Apparatus illustrating features of our invention is shown in the accompanying drawings, forming a part of this application, in which:

FIG. 1 is a wholly diagrammatic view with certain parts in section and showing a system embodying our invention which is adapted for operation of single acting rams;

FIG. 2 is a detail sectional view taken along line 2—2 of FIG. 1 and showing a detail of the main valve;

FIG. 3 is a wholly diagrammatic wiring diagram especially constructed for operating the single acting ram of FIG. 1;

FIG. 4 is a wholly diagrammatic view showing our invention in association with the hydraulic system for operating a double acting ram; and,

FIG. 5 is a sectional view through the main valve of FIG. 4.

Referring now to the drawings and particularly to FIGS. 1 and 2, we show in diagrammatic manner a ram of the single acting type indicated at 10. The plunger of the ram is indicated at 11. For the purpose of illustration, ram 11 may be the ram for the packing element of an up-packing cotton baling press. The cylinder is provided with an inlet 12 adjacent its bottom for the admission of fluid under pressure from the source presently to be described.

At 13 we illustrate an electric motor which is shown diagrammatically as driving a hydraulic pump 14. A reservoir for the fluid used is shown at 15. The pump may be provided with an automatic relief valve shown at 16 and which is in the main pressure line 17. A return line 18 leads from the pressure relief valve 16 back to the reservoir 15, in the usual manner.

In the pressure line 17 we insert a spring biased check valve 20. The pressure line then leads to the connection 12. A branch line 19 of the high pressure line leads to an opening 21 in the housing of the main flow control valve 22 of our system which will now be described.

The main control valve 22 embodies a hollow movable piston or plunger 23 which cooperates at 24 with the valve body to form a sealing seat, thus to close off passage 21 of the valve housing from a passage 26 therein. The passage 26 is connected by line 27 to return fluid to the reservoir 15.

The plunger 23 is biased downwardly by means of a compression spring 28 which rests with one end on the seat 29 of the hollow plunger 23 and at its other end against a shoulder 31. The shoulder 31 is conveniently mounted on the end of a pin 32. The upper end of the pin is welded to a member 33 that forms a T with pin 32 which is mounted in suitable manner in the valve body. An O-ring seal 34 may be provided.

It will be noted that the end 23^a of the movable piston 23 adjacent the opening 21 is smaller in area than the end 23^b, which latter end hereinafter will be referred to as the pilot end of the piston. It will further be seen that by properly proportioning the effective areas of the ends 23^b and 23^a and the pressure exerted by spring 28, we are enabled to obtain a valve which can be operated as hereinafter will be explained.

Adjacent the pilot end 23^b of the piston we provide a fluid discharge opening 36. At 37 we show an opening in communication with opening 36 and which is connected by a small branch line 38 to a small line 39. The line 39 is connected through a small check valve 41 to a branch line 42 leading to the main branch line 19. The line 38 is connected by a line 43 and through a small check valve 44 to a small line 46. The line 46 is connected at 47 to the main line 17 at a point between the pump 14 and the spring loaded check valve 20.

At 48 we show a small four-way spool type valve which may be under control of a solenoid 49 and a return spring. suffice it to say that the valve 48 of the type that when the solenoid operator 49 therefor is deenergized, oil is free to flow from the pilot end 23^b of a valve 22 through a line 51, port B, out port T, to a line 52 and thence to the tank through a line 53. Also, and as a matter of giving more volume of flow as will later appear, the valve 48 may be double ported so that fluid also flows, when the solenoid 49 is deenergized, from the port 36 through a line 56 to port P, thence to port A of valve 48, and through a line 57 to the line 53 and on to the tank. When the solenoid is energized the spool of valve 48 is moved so as to connect port A with T and B with P. The net effect of energizing the solenoid 49 therefore is to block the flow of oil from the pilot end of the main valve 22 to the reservoir 15.

Referring now to FIG. 3 of the drawings, we will now describe a suitable form of electrical circuit which adapts our invention to association with a press for baling cotton and like fibers. As will be understood, in the baling of cotton or similar fibers it is necessary to exert pressures on the order of 2,000 pounds per square inch. Once the bale is compressed ties or the like are placed around it to restrain it against expansion, the ram is then lowered (in the case of the "up packing" or single action ram), the bale is removed, the ram is raised again to "dress" the block, that is, to place the bagging about the block carried by the ram, and the ram is again lowered. With modern-day, fully automated, power driven, two box presses, it is also necessary to be assured that the ram

is out of the press box while the box moves from one position to the other. Therefore, it is for the purpose of correlating these several motions that the electrical circuit now to be described is designed to cooperate with our improved hydraulic circuit.

Referring now to FIG. 3 power for the several devices may be supplied through lines L₁ and L₂ as shown. At 61 we show a normally closed push button switch 61 in the line L₁. A switch 62 is a "stop" switch and may be a gang type switch having separate tiers 63, (normally closed) 64 (normally open) and 66 (normally open). The "up" switch is indicated at 67 and may have an upper tier 68, and a lower tier 69, both normally open.

It will be seen from FIG. 3 that the line L₁ may be connected, when all of the switches 61, 62 and 67 are closed, to the coil 70 of a relay. Relay 70 has a contact arm 71 having thereon a pair of movable contacts 71^a and 71^b which cooperate with stationary contacts 72 and 73. It will be apparent that the contact 72 cooperates with the movable contact 71^b on arm 71 to form a holding circuit for coil 70 whenever the tier 64 of switch 62 is closed; and that contact 73 cooperates with its contact 71^a on arm 71 to form a holding circuit for coil 70 whenever the tier 68 of switch 67 closes. Furthermore, it will be seen that we provide a relay having a coil 74 having a switch arm 76 carrying a contact point to cooperate with a stationary contact 77. When the switch 67 is closed it energizes and locks in the control relay coil 70, also starting the motor 13 for the hydraulic pump 14. Closing the up switch 67 also energizes and locks in control relay coil 74, energizing the solenoid 49 controlling the pilot valve 48. Pushing and then releasing the stop button of switch 62 deenergizes control relay coil 70, stopping the pump. Pushing the down switch 61 deenergizes both the coil 74 and the solenoid 49. Likewise, pushing the stop switch 62 energizes and locks in the relay coil 74 and the solenoid 49 controlling the valve 48. It will be apparent that it also momentarily energizes the pump motor so long as the stop switch 62 is held depressed. The importance of this will later appear.

Considering now the operation of the mechanism so far described and assuming the piston 11 of the ram to be in lowered position and that it is desired to raise the ram to compress a bale of cotton in a press above the ram, the following action takes place:

The "up" switch 67 is momentarily closed, having the effect of energizing the electric motor 13 for the pump 14 and energizing the solenoid 49 of valve 48. When the solenoid 49 is energized the spool of valve 48 moves to align the port B with P and the port A with T. The effect of this is merely to block off any exit of oil from the pilot end 23^b of the valve 22, shutting off any flow of fluid from the pilot end port 36 back to the reservoir 15. As has been stated, in the deenergized position of the solenoid 49 oil would be allowed to flow from the pilot end 23^b of valve 22 back to the reservoir 15. It might here be mentioned that the only reason for having a double ported valve 48 is that we are able to use a very small inexpensive valve and still provide for the required flow of oil. Having now momentarily closed the switch 67, it will be remembered that the pump 14 is being driven and that the valve 48 is connected as has just been described. Oil flows from the pump discharge up through the relief valve 16 where it encounters the spring loaded check valve 20. At the commencement of this operation the piston or movable body 23 of valve 22 will be in its lowered position with the seat 24 open, permitting any fluid in line 17 to pass through the port 21, out through the port 26 and back to reservoir 15. However, since we have provided the spring check valve 20, fluid under low pressure of the amount that the spring of valve 20 will produce (for example, 75 pounds per square inch), flows through the line 46, past checked valve 44, through line 38 into port 37 and thence into the pilot end of valve 22. In

view of the fact that the area of the end 23^b of the movable plunger 23 is very large (for example, 8.5 square inches), the low pressure developed by the spring loaded check 20 is sufficient to develop enough force to overcome the downward push (for example, 400 pounds), on the plunger exerted by spring 28. This will cause the plunger 23 to move upwardly and close off the flow of the oil from port 21 to port 26 by seating at 24. As soon as the plunger of valve 22 closes pressure builds up in the main line 17 leading to the ram. However, due to 75 pounds per square inch pressure drop through valve 20 and the differential in areas on the top and bottom of piston 23 (for example, top area 7.5 square inches, bottom area 8.5 square inches) there will be insufficient pressure on the upper end 23^a to open the valve 22. Therefore, the ram 11 rises and presses the bale to whatever density the press is set at, usually being on the order of 2,000 pounds per square inch. At this point the stop button is pressed which stops the pump motor.

Let it be assumed, now, that the ram is pressing against the bale at 2,000 pounds per square inch. It will be apparent that if the large plunger 23 by some means were suddenly moved downwardly, to open port 21 to port 26, there would be a tremendous hydraulic shock or hammering in the lines, as has been true in the past. However, with out improved system, to lower the ram the solenoid 49 is merely deenergized by pressing the switch 61, permitting valve 48 to return to the position with port B connected to T and port A connected to P. This permits a restricted flow of oil out of the pilot end of the valve 22 and into the reservoir 15, but the high pressure in the main line 17 causes oil to flow through lines 42, 39 and 38 preventing piston 23 from moving downwardly. The pilot line 46 may be a very small line, such for instance as a $\frac{3}{8}$ inch conduit as may be the lines 42, 43 and 39. Thus, as soon as valve 48 is connected as indicated by deenergizing solenoid 49, oil flows through line 42, past check valve 41, line 39, line 38, port 37, into the pilot end of valve 22, thence through the valve 48 and returns to reservoir through lines 52 and 27, and line 53. Due to the small size of the pilot lines and valve 48, there is no shock to the hydraulic system, the oil bleeding off and allowing the ram to move down at first very slowly. As the hydraulic pressure in the pilot end 23^b of valve 22 now is essentially the same as the pressure at the other end 23^a of valve 22 and this pressure is at first high, the differential in area between 23^a and 23^b (for example, 1 square inch) will cause a hydraulic unbalance larger than the force of spring 28. Thus, the plunger 23 remains in its upward or closed position until the main line pressure in lines 17 and 19 drops down into the neighborhood of that equalizing the force exerted by spring 28. At this point the plunger 23 begins to move downwardly as viewed in FIG. 1, thus to open at the sealing seat 24. This opens the large port 21 to the large port 26, whereupon the ram piston 11 begins to move downwardly very rapidly. At this point in order to roll the bale off the ram platen, the ram platen must be stopped. This is accomplished simply by momentarily closing the "stop" switch numbered 62. This has the effect of energizing the solenoid 49 and starting the pump motor 13 momentarily. The momentary energization of the pump motor provides sufficient fluid to again move the plunger 23 of the valve upwardly to close off port 21 from port 26 as described in the first step of the operation. After the bale is rolled off the ram platen the ram is moved upwardly about two feet to "dress" the block, that is to put the bagging on the follow block carried by the plunger 11. This is done by pressing the "up" button to energize the electric motor driving the pump, solenoid 49 remaining energized. To stop the ram while dressing the block the "stop" button 62 is pushed. This stops the pump from

running while solenoid 49 remains energized. It will be noted that in this condition the check valves 41 and 44 are needed to prevent the plunger of valve 22 from opening. To allow the ram to lower to its bottom position for turning the press, the "down" switch 61 is pressed, deenergizing solenoid 49, permitting valve 22 to open immediately, it being understood that the pressure in the main line is now well below the pressure exerted by the spring 28.

It will be apparent from the foregoing that the completely shockless operation of our improved system permits "push button" control with the pump unit mounted in any position relative to the press. Our invention also requires only one line from the pump unit to the ram of the press. By properly proportioning the force exerted by the spring 28 with the differential in area of the ends of the plunger 23 of valve 22, our improved system can be made to cause the main valve to open at any desired pressure in the system. It will further be understood that very small quantities of fluid only need be drained from the main system through the pilot valve 48 before the pressure is lowered sufficiently to permit safe, shockless opening of the main valve 22.

Referring now to FIGS. 4 and 5 of the drawings we show a modification of our invention adapted for association with a double acting ram. For purposes of illustration we show a ram 81 having therein a piston 82 and shown diagrammatically on the piston 82 is a follow block 83. The block 83 is designed to press against a bale of cotton or other material to compress it to around 2,000 pounds per square inch. Also, instead of packing upwardly as does the ram 10 of FIG. 1, the ram 81 packs downwardly.

The main control valve 84 may be a type of valve having an outer casing 86 and a spool 87. The spool is biased to center position by springs 88 and 89. Further, the ends of the spool are provided with pilot connection openings 91 and 92. A port 93 is adapted to be connected by a line 94 to the top of the ram 81. A port 96 is adapted to be connected by a line 97 to the lower end of the ram 81. Pressure is supplied to a port 98 through a line 99 from a pump 101 driven by an electric motor 102. Fluid returns to the tank or reservoir 103 through a line 104 connected to a port 106 in the valve body.

As seen from FIG. 5, spool 87 is provided with a restricted passage 107. The restricted passage connects the pressure port 98 to the tank port 106 whenever the valve is in centered position as shown in FIG. 5. The purpose of this restricted passage will be later explained.

At 108 we show a pilot valve for controlling the main valve 84. The valve 108 may embody a housing and spool shown diagrammatically in FIG. 4. The spool is connected by a link 109 to a shaft 111 which is under control of an operating handle 112. The shaft 111 also carries a cam 113 which rotates to the right or left as viewed in FIG. 4 whenever the handle 112 is pushed downwardly or upwardly, respectively. The motor 102 is under control of a switch 114 having a switch arm 116. The end of the switch arm falls into a notch 117 in the periphery of the cam 113 whenever the parts are in the center position shown, opening switch 114 and deenergizing pump motor 102.

It will be seen that the pressure line 99 is connected by means of a line 118, through a check valve 119 to the pressure port P of valve 108. The return line 104 is connected by a line 121 to the return port R of valve 108.

A pilot line 122 connects a port labeled 2 of valve 108 to the pilot connection port 92 of valve 84. Another pilot line 123 connects the port numbered 1 of valve 108 to the pilot connection port 91 of valve 84. A line 124 having therein a check valve 126 connects line 123 to the line 94 leading to the top of ram 81.

A line 127 is connected to line 118 between the valve 119 and line 99 and leads to a spring pressure relief valve 128. The valve 128 discharges through a line 129 to a

unit 131 which in effect is a hydraulic cylinder. The piston 132 of the cylinder 131 carries a plate 133 on its upper end and which cooperates with the lower section 134 of the cam 113 in order to center the cam whenever a pressure in excess of the setting of relief valve 128 occurs in line 127. Still another pilot line 136 having therein a check valve 137 is connected to the line 97 and leads also to a port 138 in the hydraulic cylinder 131 and connects along its length to line 121. A pressure gauge 139 may be provided in the circuit if desired. Also, a line 141 leading from the lower end of the cylinder 81, past the packing glands, may be used to drain off into a container 142 any fluid that passes the packing.

The operation of the double acting system just described is as follows:

Starting with the ram in the upward position the operator moves the control handle 112 downwardly. This closes switch 114, energizing motor 102, starting the pump which supplies fluid under pressure to line 99. Simultaneously through link 109, pilot valve 108 is shifted so that its port P is connected to its port numbered 1 and the port R is connected to the port numbered 2. Oil from the pump flows to the main valve 84, through the restricted passage 107 and back to the tank 103 through line 104. Due to the restriction of the passage 107 there will be built up a pressure, which, by way of example, may be around 400 pounds. This pressure will cause oil to flow down the pilot line 118 to the port P of valve 108. This oil will continue out the port numbered 1 of valve 108 up to the pilot connection 91 of valve 84. This shifts the spool 86 downwardly as viewed in FIG. 5, connecting port 93 with 98 and port 96 with 106 of the valve 84. This supplies oil under pressure to the top of the ram through line 94, oil in the bottom of the ram returning through line 97, port 96, port 106 and back to tank through line 104. In view of the fact that no more pressure than a maximum of, say, 400 pounds, is allowed to build up due to the restricted passage 107, the shifting of the spool 87 in the main valve 84 occurs without any shock.

With the top of the ram connected to the pressure line from the pump and the bottom of the ram connected to the tank line, the ram will descend and will continue down until either the operator shifts the handle 112 back to center, or stop position, or until enough pressure builds up in the pressure line 94 due to the resistance of the block 83 against the bale to open the relief valve 128. Once the relief valve 128 is opened oil is allowed to flow to the bottom of the plunger or piston 132 of the cylinder mechanism 131, raising the piston 132 and causing the cam blade 133 to engage the cam surface 134, thus to center the cam 113 to the position shown in FIG. 4. Oil in cylinder 131 flows to the bottom of the ram through restricted line 136. In other words, by employing the relief valve 128, piped as shown, the pressure on the bale and hence its density is automatically determined since a given pressure in the line 99 causes the recentering of the control cam 113. In the center position of the cam valve 108 has its ports 1 and 2 connected, while isolating them from either the pressure line from the pump or the return line to the reservoir. This causes an equal pressure to be exerted on either end of the main operating valve spool, permitting the springs in the valve 84 to center its spool. Centering of the spool blocks off both the top and bottom of the ram from any oil flow either in or out by blocking both top and bottom of the ram. The ram thus is held rigidly in place without the possibility of leakage upwardly. If only the top of the ram were blocked, then a small seepage by the piston rings in the ram head would allow the ram to rise because oil could flow out of the bottom of the ram as it seeped by the piston rings.

With the ram now pressing very hard against the bale and at a pressure of, say, 2,000 pounds, this pressure is present in the lines leading from the top of the ram. If the large main operating valve 84 were suddenly opened under this pressure, there would be tremendous hydraulic

shock. However, with our improvement when the handle 112 is moved upwardly the pump is energized and the pilot valve 108 is shifted to align its port numbered 1 with its port R and with its port 2 connected to its port P. Such alignment results ultimately in the spool 87 shifting to connect the top of the ram with the tank line and the bottom of the ram with the pressure line from the pump. However, initially the spool 87 is in the center position and in view of the fact that only a pressure of, say, 400 or 500 pounds can be developed by the pump due to the throttling passage 107, the 2,000 or so pounds of pressure in the line from the top of the ram will not allow the spool of the main valve 84 to shift. This is due to the provision of the line 124 leading from connection 91 to line 94. The check valve 126 in line 124 allows oil to flow only from the top of the ram to the pilot connection 91 or through line 123. Therefore, the pilot connection 91 of the valve 84 will, at this time, have 2,000 pounds per square inch force, whereas there is only 400 or 500 pounds per square inch force available to push against this pressure on the other pilot end of the main valve. It is apparent that this unbalance would actually cause the spool in the main valve to move in the opposite direction were it not for the check valve 119. It is the check valve 119 which prevents the spool 87 from shifting downward from center as viewed in FIG. 5. Since the port numbered 1 of valve 108 is now connected to the port R of that valve, oil is free to flow from the top of the ram through the pilot lines and to the tank. It is here to be noted that the pilot lines 118, 121, 122, 123, 127, 129 and 136 are very small compared to the main hydraulic lines. Consequently there is no hydraulic shock as this oil bleeds off. The ram then slowly moves upward under the force of the bale, expanding against the ties which by now have been placed around it, as the pressure bleeds off through the pilot lines. It will be understood, of course, that this pressure drops off very rapidly and actually in about two seconds it has reached the 400 to 500 pounds per square inch level below which the pressure developed in the pressure line from the pump causes the pilot pressure on the lower end of the main valve 84 to move its spool upwardly. This movement will then align the port 93 with the port 106, permitting oil in the top of the ram to flow to the tank. At the same time the port 96 will be aligned with the pressure port 98, providing oil under pressure to the bottom of the ram. The ram will then move upwardly at a very rapid rate.

The line 136 and check valve 137 are used to assure against the possibility of air entering the bottom of the ram through the ram packing during the bleeding off period of the up movement of the ram before the main valve shifts.

From the foregoing it is apparent that we have provided an improved hydraulic system in which we have substantially eliminated all hydraulic shock when depressurizing a hydraulic cylinder, ram, or other pressure device. By causing the pilot valve automatically to delay movement of the main valve while the pilot valve bleeds off the high pressure oil, we provide a system which is fully automatic, inexpensive, simple and substantially trouble free. In this specification and the appended claims, the expression "hydraulic cylinder" is intended to include also other pressurizable devices in which there exists the problem of depressurizing the same as set out herein. It is to be especially noted that in both modifications the main valves are caused automatically to follow the settings of the pilot valves, and that operating pressures for the main valves are derived from the ram operating pressure sources.

While we have shown our invention in two forms, it will be obvious to those skilled in the art that it is not so limited, but is susceptible of various other changes and modifications without departing from the spirit thereof, and we desire, therefore, that only such limitations shall

be placed thereupon as are specifically set forth in the appended claims.

What we claim is:

1. The combination with a hydraulic cylinder and a high pressure line to supply fluid under pressure to one end of the cylinder, of a hydraulically actuated main flow control valve in the high pressure line, a pilot valve, a line connecting the pilot valve to the high pressure line in fluid by-passing relation to the main valve and when in one position effective to discharge fluid directly from the high pressure line, a pair of hydraulic operating lines running directly from the pilot valve to the main valve and effective immediately upon given settings of the pilot valve to cause corresponding settings of the main valve, means to open the pilot valve before opening the main valve when the cylinder is pressurized, whereby a quantity of high pressure fluid acting on the cylinder is discharged from the cylinder through the pilot valve without opening the main valve, and means operable subsequently to the opening of the pilot valve to relieve the hydraulic operating pressure on the main valve, thereby minimizing hydraulic shock upon opening of the main valve.

2. The combination with a fluid pressure cylinder and a source of fluid under pressure, of a hydraulic pressure actuated main valve having a part movable by fluid under pressure selectively to a position to admit fluid to the cylinder and to a position to shut the cylinder off from the source of fluid under pressure, a pilot valve hydraulically connected by a pair of hydraulic lines to the main valve and effective immediately upon movement to selected positions to move the movable part of the main valve to corresponding selected positions, and hydraulic connections between the pilot valve and the cylinder through which a quantity of fluid under pressure in the pressurized end of the cylinder may be drained off without passing through the main valve, whereby the cylinder may be partially depressurized prior to opening of the main valve.

3. The combination with hydraulic cylinder and a pressure line to supply fluid under pressure to one end thereof, of a main valve having a pressure actuated movable part controlling the flow of fluid into and out of the cylinder, a pilot valve, a line connecting the pilot valve to the pressure line, another line connecting the pilot valve in operating relation to the pressure actuated movable part of the main valve, means to move the pilot valve effective hydraulically to shift the movable part of the main valve to a position to admit fluid under pressure to the cylinder by creating a hydraulic unbalance at one end of said movable part, and means to move the pilot valve to a position initially by-passing the main valve to drain off high pressure fluid from the cylinder when pressurized and subsequent thereto to remove the hydraulic unbalance on the main valve and allow passage of fluid therethrough, thereby substantially to eliminate shock upon movement of the main valve to position for fluid to flow therethrough from the cylinder.

4. In a system of the class described, a fluid pressure cylinder, a source of fluid under pressure, a main valve having a movable part controlled by fluid under pressure to admit fluid to the cylinder, to shut off fluid from the cylinder and to discharge fluid from the cylinder, a pilot valve, hydraulic connections from the pilot valve to the movable part of the main valve and effective to shift the main valve movable part to predetermined fluid admitting, fluid holding and fluid discharge positions in accordance with predetermined settings of the pilot valve, means other than hydraulic pressure urging the movable part toward position to discharge fluid from the cylinder, said hydraulic connections embodying means hydraulically to unbalance the movable part of the main valve and thereby move it to a selected position one of which is a position to admit fluid under pressure to the cylinder and to hold the fluid in the cylinder, and means included in the

hydraulic connection to bleed off a quantity of fluid from the pressurized end of the cylinder while still holding the movable part of the main valve in fluid holding position, whereby the pressure in the cylinder is reduced prior to releasing the movable part of the main valve to the action of said means urging the movable member toward fluid discharging position.

5. In a system of the character described including a hydraulic cylinder and a line leading to the cylinder and connected to a source of fluid under pressure, a main valve in said line controlling the admission and discharge of fluid to and from the cylinder, said valve embodying a fluid pressure actuated movable part for opening and closing the same, a pilot valve, hydraulic lines connecting the pilot valve to the main valve and disposed upon admission of fluid under pressure thereto to move the movable part to selected main valve positions, fluid connections from the fluid pressure line to the valve in bypassing relation to the main valve, means to shift the pilot valve to a position to pass a part of the fluid from the cylinder when pressurized through said by-passing fluid connection without changing the position of the movable part of the main valve, thereby partially to depressurize the cylinder, and means operable subsequently to the partial depressurization of the cylinder to decrease the fluid pressure in the pilot lines connecting the pilot valve to the main valve, whereby the main valve may then be moved to a position to discharge fluid from the cylinder.

20 6. The combination with a single acting hydraulic ram and a source of fluid under pressure, of a line leading from the pressure source to the ram, a main valve in said line controlling the admission and discharge of fluid from the ram, said valve embodying a movable part in the form of a differential hydraulically actuated piston which in one position connects the ram to the source of fluid under pressure and in another position discharges fluid from the ram, said pressure line being connected to exert force on the smaller end of said differential piston, means urging the piston toward fluid discharge position with a total force less than the total force generated by application of the maximum working pressure on the cylinder when applied to the larger end of the piston, a pilot line leading from the source of fluid under pressure to the larger piston end of the main valve, a pilot valve movable from a position to block flow of fluid from the large piston end of the main valve, and means to urge the pilot valve to a position to drain off a part of the fluid from the pressurized end of the ram while maintaining the main valve piston in closed position, whereby the piston shifts to ram fluid discharge position only after the ram is depressurized below that required to overcome said means urging the piston toward fluid discharge position.

25 7. Apparatus as defined in claim 6 in which the pressure line is provided with a spring loaded check valve effective to produce higher fluid pressure in one part of the pressure line than in the part thereof connected to the small piston end of the main valve, and in which the pilot line leading to the large diameter piston end of the valve is also connected to the higher pressure part of the pressure line, and in which there are check valves in the pilot line just named to pass to the larger diameter piston ends fluid under pressure from whichever section of the pressure line is under greater pressure, but not in the reverse direction.

8. The combination with a double acting hydraulic ram and a source of fluid under pressure, of a main valve controlling the admission and discharge of fluid to the ram and embodying a movable part shiftable to fluid supply and fluid discharge position upon the application of pilot line fluid pressure thereto, main lines connecting the main valve to the upper and lower ends of the ram, said main valve embodying means urging its movable part toward position to trap fluid in both ends of the

11

ram, a pilot valve, pilot lines connecting the pilot valve to the main valve whereby upon moving the pilot valve to selected positions the main valve is moved selectively to fluid admitting, fluid trapping, and fluid discharge positions, a bleed line connected to the high pressure end 5 of the ram and to the pilot valve effective when the pilot valve is in one position to bleed off a quantity of fluid from the ram when pressurized while holding the main valve in fluid trapping position, whereby the ram is partially depressurized prior to moving the same to ram 10 fluid discharge position.

12

9. Apparatus as defined in claim 8 in which the pilot valve is manually operated.
